METHOD OF AND APPARATUS FOR CURLING HAIR

Filed Nov. 3, 1925

UNITED STATES PATENT OFFICE.

PAUL E. WOLL, OF PHILADELPHIA, PENNSYLVANIA, ASSIGNOR TO PETER WOLL & SONS MFG. CO., OF PHILADELPHIA, PENNSYLVANIA, A CORPORATION.

METHOD OF AND APPARATUS FOR CURLING HAIR.

Application filed November 8, 1925. Serial No. 66,481.

My invention is an improved method and apparatus whereby hair mixtures composed of long and short hairs in various proportions may be combed, centrifugally freed of lumps, 5 clots and extraneous matter, and the aligned and cleaned hair so deposited, manipulated and fed that the lap or ribbon formed thereby may be wound into a continuous rope by twisting a section thereof. The twisting section 10 has its end adjacent to the unwound layer held against rotation and its opposite or wound end bent transversely to the axis of rotation to confine the twisting action to a section of predetermined length. The wound 15 rope is held against untwisting by being coiled on a rotary spool or reel rotating about an axis substantially parallel with the axis of rotation of the twisting sliver.

The cleaning and manipulation necessary 20 to provide a lap permitting such twisting and bending without breaking is preferably effected by feeding matted hair deposited in a continuous layer of substantially constant width and thickness to a rapidly rotating 25 toothed drum within a housing having a toothed segment, whereby the hairs are combed into parallel relation and lumps and extraneous matter therein thrown outwardly 30 into a pocket.

The refined and aligned hairs are deposited 35 in a substantially uniform lap by the drum on a belt running transversely to the drum axis. The lap is carried by the belt through a plurality of constricting and compressing devices comprising converging guide walls and 40 complementary rollers, which may have corrugated surfaces. The thoroughly worked and intermingled slivers of hair are fed by superposed belts to a condensing device having yielding pivoted blocks, by which the strand section therein is held against rotation while a projecting section thereof is 45 twisted, the wound section or rope being bent transversely to the axis of rotation of the strand and passing over capstans eccentric to the axis of rotation of the strand to a distributor by which it is fed to a rotating reel and wound thereon.

The hair is preferably moistened before 50 delivery to the combing drum and the wound rope is preferably further kinked or twisted

upon itself to form "buttons" before being subjected to steaming or baking to set the curl therein.

Characteristic features and advantages of 55 my invention will further appear from the following description and the accompanying drawings of a machine illustrating something diagrammatically apparatus embodying 60 my invention and adapted for the practice of my improved method.

In the drawings, Fig. 1 is a longitudinal 65 sectional view, partly in section, of apparatus adapted for the practice of my invention and embodying the structural features thereof; 70 and Fig. 2 is a top plan view of the apparatus shown in Fig. 1.

As illustrated in the drawings, a frame 1 supports a housing 2 enclosing a rotary toothed drum 3 journaled in the frame and rotated at high speed through a fast-and-loose pulley 4 by a belt 5. The curved upper segment 2' of the housing is provided with internal teeth 6 complementary to the drum teeth 7. The passage of the hair between the teeth 6 and 7 straightens and smooths the fibres thereof, and any lumps not disintegrated by the teeth and any extraneous matters are thrown by centrifugal force from the drum into the pocket 2" of the housing. 75

The crude hair is supplied to the drum teeth through the housing inlet 8 by an endless apron 9 on which the crude hair is placed between guideways 10 in a layer of substantially uniform thickness and width for a mixture of given proportions. The apron 9 is supported and operated by the rolls 11 and 12 connected by a sprocket chain 11', and the roll 12 has fixed thereto a gear 13 meshing with a gear 14 on the cone pulley 15. A roll 16, 80 journaled in the frame, is rotated by the roll 12, through the meshing gears 17 and 18, and coacts with the roll 12 to compress the matted hair and insure delivery thereof to the drum teeth. The cone pulley 15 is connected 85 through a belt 15^a, pulley 15^b, shaft 15^c and gears 15^d with the driving shaft 15^e.

The delivery end of the housing 2 has converging walls projecting therefrom and is open to the atmosphere to avoid the formation 90 of eddies or swirling air currents. The cleaned and combed hair is delivered by the

drum teeth 7 through the opening in an even layer to the conveyor belt 19 carried over the rollers 20 and 21; a guard 22 being disposed between the drum and the end of the belt. 5 The lap of deposited hairs is compressed in thickness by spring pressed compression rollers 23 and 24, and is carried by the conveyor belt 19 between the converging guide walls 25 and 26, which may be made adjustable 10 to constrict the width of the lap at the desired rate and to the desired extent.

The constricted lap is compressed in thickness or depth and somewhat expanded in width by pairs of spring pressed compression 15 rollers 27, 28, 27', 28' suitably geared together by gearing 29 and rotated from the sprocket chain 29' driven by a sprocket gear 30 on the shaft of the roller 21.

Converging guide walls 31 and 32, which 20 may be made adjustable, again constrict in width the lap flattened by the compression rollers 27, 28, 27', 28' and the constricted lap is again compressed between the spring pressed roller 34 and the roller 21. The roller 34 is connected with the roller 21 by suitable gearing and the shaft of the roller 21 has on one end thereof a gear 35 and on the other end a gear 35' meshing with a pinion 36 on a cone pulley 37 driven through the belt 38, cone 30 pulley 39, sprocket chain 40, pulley 41 and belt 42.

The lap, compressed in thickness and expanded in width by the action of the rollers 21 and 34 is again constricted in width by 35 guide plates 42 and 43, which may be made adjustable. The resulting ribbon of hair is fed between superposed endless belts 44 and 45, the belt 44 being carried and translated by rolls 47 and 48, connected by endless bands 40 46', and the belt 45 being carried and translated by the rollers 47' and 48'. The rollers 48, 48' are connected together by suitable gearing thereon; the rollers 47, 47' are connected together by suitable gearing and the roller 47' is driven from the gear 35 through 45 an idler 35''.

The rollers 47 and 48 are journalled in 50 stringers 49 so that the upper traveling belt 44 may be turned about the axis of the shaft 47 to raise one end thereof and give access to the space between these belts 44 and 45, whose adjacent surfaces travel in the same direction and are adjustable relatively to one another to secure desired pressure on the ribbon of hair passing between them.

The ribbon discharged from the belts 44 and 45 is further condensed in cross section by passage through a longitudinal channel with flaring ends in the block 50 through 60 which the ribbon passes under control of the grooved blocks 51 and 52 pivotally mounted in the block 50 and pressed by adjustable weights 53 and 54 against the ribbon of hair with sufficient force to restrict and substantially prevent rotation thereof.

The ribbon or strand of hair projecting from the condenser 50 is twisted into rope by rotatable spinning apparatus 55 having a hollow tube or spindle 56 journalled in bearings 57 and driven through suitable gearing 70 58 from a pinion 59 detachably connected with the shaft 60 to permit substitution of pinions of different diameters and thereby vary the number of turns in the rope per unit of length. The shaft 60 is connected through 75 the pulley 61, belt 62, and pulley 63 with the driving shaft 15°.

On emerging from the end 64 of the tube 56, the rope is bent transversely and passes over journalled capstans 65 rotated by gears 80 66.

A spool or reel 67 is detachably mounted on the spindle 68 and latched to a rotating flier or frame 69 which is journalled in the bearings 69' and rotated through suitable 85 gearing 70 from the shaft 60. The spool is rotatable by the flier about an axis coincident with or substantially parallel with the axis of rotation of the tube 56 and of the section of hair being twisted. A distributor 71 is 90 reciprocable axially along the spool by usual automatic feeding and reversing mechanism 72 and feeds the rope from the capstans to the spool in parallel loops.

From the foregoing, it will be observed 95 that I have provided hair curling apparatus whereby matted hair placed in a layer of substantially constant depth and width on the apron 9 is combed and cleaned by the toothed drum 3 and deposited in a passageway having a plurality of contracted throats constricting the width of the hair layer carried therethrough by the travelling conveyor 19. Compressing rolls are positioned adjacent to each throat to compress the 100 thickness and expand the width of the travelling lap, which is finally condensed to small cross sectional area by passage through the condenser 50. The twisting of the lap is localized by the action of the blocks 51 and 105 the wound rope is bent and drawn over the capstans and through the distributor by the rotating spool. When one spool is filled, it 110 is removed and replaced by an empty spool. The rope wound on the spool is subsequently 115 twisted further so as to form "buttons" and steamed or baked to set the curl therein, after which the rope is disintegrated into its fibres, which retain their curl and springy condition.

Having described my invention, I claim:

1. The method of curling hair which comprises combing the fibres and centrifugally separating lumps or extraneous matter therefrom, depositing the fibres in a lap, repeatedly compressing the thickness and thereafter constricting the width of the lap, twisting a section of the lap into a rope, bending the rope transversely to the axis of the twisting section, and coiling the rope about 120 125 130

an axis parallel with the axis of the twisting section.

2. Apparatus for curling hair comprising a toothed drum, a toothed housing for said drum, means forming a pocket in said housing for receiving matter thrown off from said drum, means for feeding hair to said drum, said housing having an open front opposite

said feeding means, means for repeatedly constricting the width and compressing the thickness of hair deposited by said drum, and means for curling said deposited hair.

In testimony whereof I have hereunto set my name this 28th day of October, 1925.

PAUL E. WOLL.
